United States Patent Office

Des. 182,766
Patented May 13, 1958

182,766

JEWEL BOX

William H. Hardy, River Edge, N. J.

Application October 28, 1957, Serial No. 48,255

Term of patent 3½ years

(Cl. D86—9)

FIG. 1

FIG. 4

FIG. 2

FIG. 3

FIG. 5

Fig. 1 is a top plan view of a jewel box showing my new design;

Fig. 2 is a front elevational view thereof;

Fig. 3 is a side elevational view thereof;

Fig. 4 is a rear elevational view thereof;

Fig. 5 is a top plan view with the cover open.

The entire top surface of the box is covered with stones of graduated sizes in the area indicated by the broken lines in Figs. 2, 3, and 4.

I claim:

The ornamental design for a jewel box, substantially as shown and described.
